UNITED STATES PATENT OFFICE.

DARIUS B. SPEER, OF BLUE GRASS, IOWA.

MACHINE FOR CUTTING GREEN CORN FROM THE COB.

SPECIFICATION forming part of Letters Patent No. 295,831, dated March 25, 1884.

Application filed December 3, 1883. (No model.)

To all whom it may concern:

Be it known that I, DARIUS B. SPEER, a citizen of the United States, residing at Blue Grass, in the county of Scott and State of Iowa, have invented a new and useful Machine for Cutting Green Corn from the Cob, of which the following is a specification, reference being had to the accompanying drawings.

This invention relates to machines for cutting green corn from the cob for canning and other purposes; and its object is to provide a machine of this class possessing superior advantages in point of simplicity, inexpensiveness, durability, and general efficiency.

In the drawings, Figure 1 is a side elevation of a machine embodying my improvements. Fig. 2 is a vertical longitudinal sectional view of the same. Fig. 3 is a detail transverse sectional view through the hopper, taken on the line $y-y$, Fig. 1. Fig. 4 is a detail sectional view taken through the driving-rod of the feed-rolls, the lever-block, and the safety-pin on the line $x-x$, Fig. 3. Fig. 5 is a rear end view of the machine. Fig. 6 is a detail longitudinal sectional view taken through one of the knife-arms. Fig. 7 is a detail transverse sectional view taken through one of the scrapers. Fig. 8 is a detail transverse sectional view taken through one of the guards. Fig. 9 is a detail perspective view, partly broken away, illustrating the plunger-rod and plunger-head.

Referring to the drawings, A designates a suitable bed-plate or table, which is preferably mounted upon legs B, and is provided at its front end with bearings C C, for a transverse crank-shaft, D, having a band-wheel, E, or other means for communicating motion to the shaft. The crank-shaft is connected by a pitman, F, with a cross-head, G, sliding between guides H H, disposed longitudinally on the table A, which cross-head carries a plunger-rod, I, having a sleeve, J, forming the plunger-head. Around the plunger-rod, and between a shoulder, i , on the rod and an interior shoulder, j , on the sleeve J, is disposed a coiled spring, K, which acts against the sleeve to retain it in its normal position at the rear end of the plunger-rod, the action of the spring being limited by heads or enlargements j' , on the front ends of bars $j^2 j^2$, which

pass through eyes g in lugs g' on the cross-head and project forwardly from an annular lateral flange, j^3 , at the front end of the collar J. This plunger and plunger-head pass through a corresponding opening, l , in a suitable frame, L, which projects from table A at the front end of the hopper Q, and the operation of the plunger is as follows: On its rear stroke the plunger-head forces the ear of corn from the hopper to the cutting-knives, when the flange j^3 engages the front face of the frame L and holds the collar or plunger-head against the tension of the spring K to prevent the plunger-head from going between the knives. Thus the plunger-head is retained stationary while the plunger-rod continues the rearward stroke to force the ear from between the knives to the scrapers beyond; but as soon as the forward stroke of the plunger-rod begins the tension of the spring returns the plunger-head to its normal position.

M is a suitable frame, projecting upward from the table A at the rear of the hopper, and provided with an opening, m , registering with the opening l , and likewise adapted for the passage of the plunger. Between these plates or frames L and M are journaled two approximately semicircular feed-rolls, N and O, arranged, respectively, one above the other, and each provided with two longitudinal parallel semicircular grooves, $n n o o$, in their adjoining faces, as shown. These rolls are connected by an endless encircling belt, P, which is secured to the rolls by pins or screws $p p$, so that the said rolls will positively move together. At each side of the rolls is arranged an inclined feed-board, Q, which form the hopper, the feed from this form of hopper being very rapid, as the bottom feed-roll alternately takes the corn from each side. The rolls simply rock upon their pivots, and the groove in the down side of the bottom roll receives an ear of corn and carries it up to the plane of the openings l and m as the top roll turns far enough to catch the ear, which latter is thus held between the corresponding grooves of the two rolls, as shown in Fig. 3, until the plunger forces it through the opening m onto the knives. The operation of the rolls is effected by two cross-levers, R R, which are pivoted to the under roll and to the ends of a lever-block, S,

which is retained on a transversely-reciprocating drive-rod, T, by means of flanges *s s*, and by a safety-pin, U. The flanges *s s* obviate vertical displacement of the block S, and the 5 said pin U normally locks the block to the shaft and retains it from longitudinal movement on the same. This pin U is seated in a suitable casing, U', which is secured to the under side of the rod T. The said casing contains a coiled spring, *u*, which exerts its tension upon the pin U to force the beveled head *u'* of the said pin through the rod T and into a correspondingly-beveled notch, *s'*, in the under side of the block S. With this construction, if the feed should become irregular and cause clogging or gorge in the rolls, or if an ear of corn should engage the rolls in an end-wise manner, the rolls will be locked against movement, and will cause a corresponding 10 stoppage of the block S, while the power of the drive-rod T will overcome the tension of the spring *u*, and will force the pin U from engagement with the block S, and permit the drive-rod to make its movement, while the 15 block S will remain stationary, and thus no damage will ensue to the rolls or any other part of the mechanism. The drive-rod reciprocates in openings *a a* in the frame A, and is provided at the side of the latter with a plate 20 or enlargement, *t*, having a vertical slot, *t'*, which is curved at each side at its central portion, *t''*, as shown, the purpose of which will be presently described. At the outer side of this eye portion *t* is provided an extension, *t''*, 25 of the drive-rod, which extension moves in guide-slots *v v* in a lateral auxiliary frame, V, secured to the base-plate A. In this frame V are provided bearings *v' v''* for the cranked end *w* of a longitudinally-extending crank-rod, W, 30 which is provided at its other end with a bevel-gear, *w'*, which meshes with a corresponding gear, *d*, on the end of the main crank-shaft D, and thus motion is transmitted from the main crank-shaft. The crank end *w* of the 35 shaft W engages the slot *t'*, and as the shaft W is rotated the said crank end *w* will slide in the slot, and will act against the drive-rod, when the end engages the straight top part of the slot, to force the drive-rod in one direction. 40 This action effects the elevation of an ear of corn by the under roll, and, as the crank end *w* passes over the curved portion *t'*, it simply holds the drive-rod and roll until the ear of corn has been pushed in between the knives and the plunger has partly returned. 45 Then the crank end *w* engages the next straight portion of the slot, and the drive-rod is forced in an opposite direction.

X designates four rearwardly-projecting 50 arms, which extend from the frame M, and are provided at their rear ends with perforations *x*, in which the knife-shanks *y* are adjustable against a coiled spring, Z. In the front faces of these shanks are provided 55 grooves *x'*, in which the stems *A²* of the knives *A⁵* are fitted, these stems being provided with

slots *a²*, through which pass securing-bolts *B²*, extending also through perforations in the shanks *y*, and nutted by a block, *C²*, to which the rear end of the guards *D²* are hinged. 70 By operating the bolts *B²*, the nuts or blocks *C²* may be readily loosened or tightened, so that the knives may be readily adjusted. The front ends of the guards are pivoted to rods *E²*, passing through perforations in the front 75 ends of the arms X. These guards are preferably provided with a concaved engaging edge.

F² designates the scrapers, which are of right-angular form, and are pivoted, as shown 80 at *s⁵*, at the vertex of the angle to the shank *y* in front of the knives, and have their top ends acting against a spring or cushion, G², as shown. These scrapers serve to remove the particles of grain which remain on the 85 cob after the latter has passed through the knives.

I claim as my invention—

1. In a machine for cutting corn from the cob, the combination of a hopper-feeding 90 mechanism embodying two rolls, arranged one above the other, and provided with concave or semicircular grooves in their adjoining faces, with mechanism for rocking these rolls together, substantially as set forth.

2. In a machine for cutting corn from the cob, the combination of the herein-described hopper mechanism, comprising the two semicircular rolls, journaled one above the other, and provided with two parallel semicircular 100 grooves in their adjoining faces, inclined feeding-boards arranged at each side of the rolls, devices connecting the rolls so that they will move positively together, and mechanism for rocking the rolls upon their bearings, substantially as set forth.

3. In a machine for cutting corn from the cob, the combination of feeding-rolls having 110 grooves in their adjacent faces to receive the ears of corn, a reciprocating drive-rod, cross-levers connected with the drive-rod and with one of the rolls, and operative mechanism to transmit a rocking motion to the latter, substantially as set forth.

4. The combination of the feed-rolls having 115 grooves in their adjoining faces, a drive-rod, mechanism for reciprocating the drive-rod, a lever-block connected with the drive-rod, and provided with a beveled notch, operating-levers pivoted to this block and to one of the 120 rolls, and an automatic spring-actuated safety-pin engaging the notch, and adapted to become automatically disengaged by accidental gorge in the feed, substantially as set forth.

5. The combination of the feed-rolls having 125 the grooves in their adjoining faces, devices connecting the rolls, a transverse reciprocating drive-rod having a vertical slot in its end, cross-levers connecting this rod and the under roll, a crank-shaft engaging the said slot, and operative mechanism, substantially as set forth.

6. The combination of the frame of the ma-

chine, the main crank-shaft, the plunger connected with said shaft, the feed-rolls journaled one above the other, and having the grooves in their adjoining faces, devices connecting these rolls together, a transverse drive-rod having a vertical slot curved or expanded at its central portion, devices connecting this rod and one of the rolls, and a crank-shaft engaging the slot and connected with the main crank-shaft, substantially as set forth.

7. The combination, with the stem of the knife containing the spring or cushion, of the approximately right-angular scraper, fulcrumed at the vertex of the angle, and acting against the cushion, substantially as set forth.

8. The combination of the cutting mechanism embodying the stem of the knife, the

blade having a slotted shank, the nut, the securing-bolt passing through the stem, the shank, and the nut and the guards hinged to the said nut, substantially as set forth.

9. The combination, with the plunger-rod, of the tubular plunger-head having the annular flange at its end, the interposed spring, and devices extending from the flange to the plunger and limiting the action of said spring, substantially as set forth.

In testimony that I claim the foregoing as my own I have hereto affixed my signature in presence of two witnesses.
